CLAIM

I claim the ornamental design for a storage panel, as shown.

DESCRIPTION

FIG. 1 is a rear isometric perspective view of a first embodiment of a storage panel.

FIG. 2 is a front isometric perspective view of thereof.

FIG. 3 is an isometric top view thereof.

FIG. 4 is an isometric bottom thereof.

FIG. 5 is an isometric left elevational view thereof.

FIG. 6 is an isometric right elevational view thereof.

FIG. 7 is an isometric rear elevational view thereof.

FIG. 8 is an isometric front elevational view thereof.

FIG. 9 is a front isometric perspective view of a second embodiment of a storage panel.

FIG. 10 is a rear isometric perspective view of the second embodiment.

FIG. 11 is an isometric top view of the second embodiment.

FIG. 12 is an isometric bottom of the second embodiment.

FIG. 13 is an isometric right elevational view of the second embodiment.

FIG. 14 is an isometric left elevational view of the second embodiment.

FIG. 15 is an isometric front elevational view of the second embodiment.

FIG. 16 is an isometric rear elevational view of the second embodiment.

FIG. 17 is a rear isometric perspective view of a third embodiment of a storage panel.

FIG. 18 is a front ear isometric perspective view of the third embodiment.

FIG. 19 is an isometric top view of the third embodiment.

FIG. 20 is an isometric bottom of the third embodiment.

FIG. 21 is an isometric left elevational view of the third embodiment.

FIG. 22 is an isometric right elevational view of the third embodiment.

FIG. 23 is an isometric rear elevational view of the third embodiment.

FIG. 24 is an isometric front elevational view of the third embodiment.

FIG. 25 is a front isometric perspective view of a fourth embodiment of a storage panel.

FIG. 26 is a rear isometric perspective view of the fourth embodiment.

FIG. 27 is an isometric top view of the fourth embodiment.

FIG. 28 is an isometric bottom of the fourth embodiment.

FIG. 29 is an isometric right elevational view of the fourth embodiment.

FIG. 30 is an isometric left elevational view of the fourth embodiment.

FIG. 31 is an isometric front elevational view of the fourth embodiment; and,

FIG. 32 is an isometric rear elevational view of the fourth embodiment.

Broking lines in the drawings show portions of the storage panel that form no part of the claimed design.
